UNITED STATES PATENT OFFICE.

HENRY A. GURRIES, OF PALO ALTO, CALIFORNIA.

BENCH-STOP.

1,269,703.

Specification of Letters Patent. Patented June 18, 1918.

Application filed August 15, 1916. Serial No. 114,994.

To all whom it may concern:

Be it known that I, HENRY A. GURRIES, a citizen of the United States, and a resident of Palo Alto, county of Santa Clara, State 5 of California, have invented a new and useful Bench-Stop, of which the following is a specification.

My invention relates to bench stops.

An object of my invention is to provide 10 a bench stop which can be adjusted with the fingers unaided by a tool.

Another object of my invention is to provide a bench stop having a vertically adjustable V-block therein.

15 Another object of my invention is to provide a bench stop having a vertically adjustable V-block and retaining points for holding the end of the work in the V-block.

The invention possesses other features of 20 advantage, some of which, with the foregoing, will be set forth in the following description of the preferred form of my invention which is illustrated in the drawings accompanying and forming part of the 25 specification. It is to be understood that I do not limit myself to the showing made by the said drawings and description, as I may adopt variations of the preferred form within the scope of my invention as set forth 30 in the claims.

Referring to the drawings:

Figure 1 is a top view of the bench stop of my invention, portions being broken away to show the construction.

35 Fig. 2 is a vertical section of the bench stop taken on the line 2—2 of Fig. 1.

Fig. 3 is a front elevation of the bench stop arranged in the top of a bench, portions being broken away to show the construction. The dog is shown in the raised position.

40 Fig. 4 is a fragmentary side view of the stop showing the V-block in the raised position. Portions are broken away to disclose the structure.

45 Fig. 5 is a top view of a modified form of bench stop, the V-block being raised.

Fig. 6 is a fragmentary vertical section of the bench stop shown in Fig. 5, taken on 50 the line 6—6 of that figure.

Fig. 7 is a vertical section of the bench stop similar to Fig. 6, but with the V-block in its lower position. A fragment of the bench top in which the stop is set is also 55 shown.

Figs. 8 and 9 are fragmentary front ele-

vations of the bench stop showing the V-block in the low and raised positions respectively. Portions are broken out in both figures to show the construction.

60

Fig. 10 is a top view of a modified form of my invention.

My invention includes an outer shell which is secured in a suitable aperture in the bench top. Within the shell are two 65 members normally lying together and capable of being pulled up by the fingers, as a unitary structure to serve as a dog or stop, against which a board may be planed. One of these two members is capable of being 70 raised alone from the rest of the structure and its shape is such that it provides a V-block into which the end of a board is adapted to lie. Means are provided for retaining the board in the V-block, while the 75 edge is being jointed.

Referring first to Figs. 1 to 4 inclusive, a shell 6 is provided in which the other members of the device are contained. Preferably the shell is formed of sheet metal 80 and is of such section that it will fit a round hole which has been squared out on one side. Within the shell 6 is closely fitted a member 7 preferably of cast steel in the forward surface of which a V-shaped groove has been 85 cut. In Fig. 1 this groove is indicated by the lines 8 and 9. For the sake of lightness the member 7 is recessed at both sides, leaving an edge 12 on the rear, and edges 13 and 14 at the front corners, to bear against the 90 inside of the shell and maintain the position of the member therein. The member 7 constitutes the V-block in my bench stop and it is vertically adjustable within the shell 6, so that it may be extended to a greater or 95 less height above the top of the bench as needed.

Arranged within the groove of the V-block 7 is a center block 16 of triangular section preferably also of cast steel and 100 formed hollow for the sake of lightness. The center block 16 is shaped to fit the space formed by the V-groove and the front wall 6^a of the shell 6 and is slidable therein. At the lower end of the block 16 is secured a 105 spring 18 which frictionally engages the shell wall 6^a, pressing the block 16 into the groove and the V-block 7 against the rear of the shell 6, thus maintaining both center block and V-block in position within the 110 shell.

If desired, a flange or ears 21, Fig. 5,

may be formed at the top of the shell to position the latter in the bench top 22, but a cleat 23, Fig. 3, may be secured on the under side of the bench for the same purpose.

At the upper front portion of both block and V-block, a roughened surface 25 is provided. This surface juts out from the front of the blocks and provides a non-slip contact against which the work bears when my device is used as an ordinary stop as in Fig. 3. In such a use, the blocks 7 and 16 constitute a dog and act as a unitary structure, their top surfaces being flush. If, however, a board is to be jointed on its edge, the V-block 7 is pulled up alone leaving the block 16 stationary as in Fig. 4. The V-block may be raised to the height desired, where it remains owing to the frictional contact with the shell caused by the spring 18. A notch 27 formed in the back of the V-block provides means for securing a hold whereby the block may be raised and preferably the bench 22 is recessed at 28 and 29 to facilitate engagement of the fingers with the dog as a whole.

Means are provided for engaging the bottom edge of a board held in the V-block so that it is not easily disengaged therefrom.

A bar 31 is pivotally mounted in the top of the block 16, notches or bearings 32 being cut in the walls of the block to receive the bar. The bar is retained in the bearings by the plate 16^a secured on the top of the block 16 by the screws 34. On the end of the bar 31 is an arm 35 which lies within a groove 36 formed in the V-block. At the top, the groove 36 is widened abruptly to form a shoulder 37, best shown in Fig. 4. The bar is provided with suitably spaced retaining points 39 which normally lie below the top 16^a when the V-block 7 and the block 16 are together with their top surfaces flush as in Fig. 2. As the V-block 7 is drawn up and away from the block 16, the arm 35 is wiped over the shoulder 37, thus rotating the bar and turning the points 39 upward through the apertures 41 in the plate 16^a into a vertical position. This relation of parts with the V-block raised is shown in Fig. 4, the arm 35 bearing against the side of the groove 36 and the points 39 bearing against the left ends of the apertures. The retaining points in this position engage the bottom edge of the piece which is inserted in the V-block, retaining the piece therein. Obviously but one retaining point may be used, but I prefer two spaced as shown, since matched boards are more easily retained thereby. When the V-block is no longer needed it is pushed down flush with the center block, and means are provided for causing the retaining points to be turned down below the surface of the center block when the V-block is lowered to this position.

A pin 38 is arranged in such a position that as the V-block approaches the lower position, the arm 35 is engaged by the pin and turned downwardly to lie across the shoulder 37. This turns the bar and hence the points 39 into the position shown in Fig. 2. It is thus apparent that the retaining points 39 follow the movement of the V-block, turning up during the first portion of the upward movement of the V-block and turning down during the last portion of the downward movement.

Means are provided whereby the raising of the retaining points is avoided if it is desired to dispense with them in the use of the V-block. The bar 31 is arranged to slide longitudinally in its bearings in the center block. A spur 42 is secured to the bar so that this longitudinal movement may be effected, the spur projecting a small amount above the surface so that it may be engaged by the thumb nail. A notch 43 is formed in the top plate 16^a to accommodate the spur when the bar 31 is shifted to the side. At the side of the groove 36 is a second groove 44. When it is desired to raise the V-block without the retaining points, the spur 42 is pushed over into the notch 43 thus carrying the bar 31 to the right and alining the arm 35 over the groove 44. When the V-block is now raised, the arm is not moved by the shoulder 37, but lies unengaged in the groove 44. Movement of the spur 42 to the left as in Fig. 1, places the arm 35 in position to be engaged by the shoulder 37 as first explained. A notch 45 is left in front of the spur 42, in which it may lie when the bar is turned to elevate the points.

In Figs. 5 to 9 inclusive I have shown a modified form of my invention. The main difference between the two types lies in the means for effecting the automatic movement of the retainer. In this instance the block 16 is preferably formed with an integral top. The sides are pierced with L-shaped holes 51 in which lie the retainer bar 31, preferably of rectangular section in this case. Between the bar 31 and a bridge 53 spanning the front of the block is disposed a flat spring 55 the function of which is to press the bar upward to the top of the holes 51 as in Figs. 6 and 9. The bar 31 is provided with points 39 conveniently inserted therein after the bar has been seated in position in the block. The ends of the bar 31 project from the sides of the block to engage grooves 57 formed in the walls of the V-block. The upper portion of the grooves 57 are offset a small amount and the width is such that the ends of the bar travel in the groove without binding.

When the V-block 7 and block 16 are together as shown in Fig. 7 with the upper surfaces flush, they may be used as a stop, the

two blocks being drawn up to the desired height as though composed of but a single member. In this position the bar 31 is held down in its lowest position by the engagement of its ends with the top wall 58 of the groove 57 as shown in Fig. 8. The spring 55 is now under tension and the ends of the retaining points are in the inactive position below the surface of the block 16. If it is desired to use the V-block, it is pulled up to the position required as previously explained. With the first upward movement of the V-block the pressure of the top wall 58 of the groove is removed from the ends 15 of the bar which is raised to the top of the holes 51 by the spring 55. This position is shown at B, Fig. 6. With a further upward movement of the V-block, the bar is bodily moved forward, *i. e.*, the left of Fig. 6, to 20 rest upon the seats 61, by the action of the offset grooves 57 in which the ends of the bar engage. The parts are now in the position shown in Figs. 6 and 9, the bar resting on the seats 61 and the points 39 bearing 25 against the front of the apertures 42 and projecting through the top of the block to engage the piece held in the V-block. When the V-block is pushed downwardly, the action of the grooves 57 moves the bar 31 to 30 the rear, *i. e.*, the right of Fig. 6, and then as the top 58 of the groove strikes the ends of the bar, it is forced downwardly against the resistance of the spring 55 to its low position as shown in Figs. 7 and 8.

35 In using the V-block to hold a board while jointing its edge, the board is pushed into the V-block as far as possible and above the level of the retaining points and then forced downwardly into engagement with the 40 points, which secure it in position, and prevent its accidental withdrawal.

In Fig. 10, I have shown a modification of the structure shown in Fig. 1. The center block and the outer shell are united in one 45 member 51 and the V-block 7 is movable within this member. The V-block in this construction is raised a small amount with or without the retaining points, to serve as a dog in the ordinary use of the bench stop, 50 or it may be raised the full height to serve as a V-block for supporting wide boards on edge. The front edges of the V-block are

preferably roughened to better hold the work as indicated at 25^a, Fig. 3.

I claim:

- 55 1. In a bench stop, a vertically adjustable dog comprising a center block and a V-block adjustably arranged on said center block.
2. In a bench stop, a vertically adjustable center block, a vertically adjustable V-block, 60 and retaining points for said V-block arranged on said center block.
3. In a bench stop, a vertically adjustable center block, a vertically adjustable V-block, 65 retaining points for said V-block arranged on said center block, and means for raising said points into operative position automatically when the V-block is raised.
4. In a bench stop, a vertically adjustable 70 dog comprising a center block and a V-block adjustable upon said center block, and means arranged in the top of said center block for retaining a piece of work in said V-block.
5. In a bench stop, a vertically adjustable 75 dog comprising a center block and a V-block adjustable upon said center block, a bar provided with retaining points arranged in said center block and adapted to be moved to bring said points into operative position 80 by the movement of said V-block.
6. A bench stop comprising a shell adapted to fit an aperture in the top of said bench, a vertically adjustable dog disposed in said shell, said dog comprising a center 85 block and a separately adjustable V-block, and means for retaining a piece of work in said V-block.
7. A bench stop comprising a shell, a vertically adjustable dog frictionally disposed 90 in said shell, said dog including a center block and a V-block, means for retaining a piece of work in said V-block and means operated by the relative movement between said center block and said V-block for throwing said retaining means into operative and inoperative position.

In testimony whereof, I have hereunto set my hand at San Francisco, California, this 8th day of August, 1916.

HENRY A. GURRIES.

In presence of—
C. S. EVANS.
